METHOD AND APPARATUS FOR TREATING YARN

Johann Joseph Stoeckly, Teltow-Seehof, Germany, assignor to North American Rayon Corporation, New York, N. Y., a corporation of Delaware

Application June 25, 1936, Serial No. 87,133
In Germany June 27, 1935

3 Claims. (Cl. 91—55)

The present invention relates to the manufacture of yarns of cellulosic origin but more particularly has for its purpose to devise an improved finishing process.

5 It has long been known in the industry that textile fabrics made from cellulose yarns have a tendency to wrinkle to an excessive degree. A number of processes have been known and used for the sole purpose of eliminating the wrinkling 10 of the fabrics. In one of these known processes the goods are impregnated with solutions of artificial resin such as formaldehyde condensation products; the latter solutions are then precipitated upon and within the threads by means of 15 high treating temperatures.

Whereas in the treatment of fabrics made from 20 yarns of cellulosic origin some success has been achieved in eliminating wrinkling, in the treatment of the yarns themselves, no satisfactory results have been obtained. Where treating steps 25 have been taken the results have been at best most irregular. In the majority of cases, certain portions of the yarn were found incapable of enduring the high and long treating temperatures necessary for the success of the process. The result was that the yarn became hard and brittle and lost a certain amount of its elongation 30 properties and that the yarn was therefore not as suitable for weaving purposes as before the finishing treatment had been given to it.

It has been found through extensive experimentation that the unsatisfactory results were largely due to the fact that the yarn had been treated either in the form of a wound package 35 or in skeins. It was further found that uniform impregnation did not occur when whole yarn packages or skeins were fully saturated. It was also found that the impregnating substances concentrated at those places in the yarn package 40 which had been most thoroughly dried.

It is therefore one object of the present invention to devise a process which will satisfactorily eliminate the wrinkling of cellulose yarns, i. e., 45 yarns made from natural textiles, such as cotton, linen and the like, or artificial silk or staple fibre.

These and other objects of the present invention will in part become obvious and part be pointed out in the following specification and the appended claims taken in conjunction with the 50 attached drawing. The drawing shows a schematic view of a preferred form of a device carrying out the process comprising the invention.

The present invention comprises saturation of 55 the thread during heat treatment or the condensation process may be carried out at a high temperature and on a continuously moving single thread. The impregnation and/or hardening liquids employed may be of the same kind as 60 heretofore used for similar purposes, i. e., solu-

tions and emulsions of artificial and natural resin, and the like.

It is preferred to draw the yarn from large packages such as cross-wound bobbins or cones and to lead the thread for its impregnation first 5 through a device containing a hardening liquid. For this purpose, the thread is first immersed and then passed over a guiding device having a sponge or felt body whereby excess liquid may be removed from the thread. Other devices such as 10 are used for the continuous oiling or sizing of thread may also be employed.

The thread loaded with a limited amount of 15 hardening liquid is then dried in a continuous operation and heated thoroughly and the desired 20 hardening effect is thus obtained. Thereafter the thread is collected or wound in any well known manner.

It is essential that not only the temperature 25 to which the thread is subjected be kept within certain limits, but that also the length of time 30 of heating is accurately gauged and the heating process discontinued.

The drying and heating device for so-called 35 continuous thread apparatus which have been 40 employed hitherto in the unwinding of the yarn 45 may be used. For example, drying rollers and roller-like devices and combinations thereof 50 which make it possible to advance the thread in a continuous helix may be used. The heating 55 rollers may be heated from the inside in any well known manner, either by hot oil or by electrical means or with super-heated steam. It is believed, however, that the heating of the drying 60 rollers by direct contact with gas flames either 65 from the outside or the inside is preferable as shown in Fig. 2 of the drawing.

The treating device may be constructed in the 70 form of a longitudinal machine which is provided along its lower end with a liquid container and 75 into which the thread is drawn whereby a thorough saturation with the impregnating fluid takes place. A drying cylinder is arranged above this 80 container, over which the thread is passed a plurality of times for the drying and hardening 85 thereof. The guidance of the thread around the cylinder a plurality of times may be accomplished by using ordinary thread guides, thread guide grates or guiding rollers. The necessary winding 90 device is arranged above the drying device. It may consist of winding devices for cross-wound bobbins, the shafts of which may be arranged in longitudinal direction of the machine 95 whereby all of the bobbins may be served by a common traverse guide. By means of the above 100 arrangement, it will be possible to provide a board along the lower end of the machine upon which a large number of yarn packages, for example, fifty or one hundred, may be placed. From these 105 yarn packages the thread may then be drawn off 110

- by reason of rotation of the yarn support or the thread may be drawn vertically if the yarn body is stationary and is then passed through the impregnating fluid by means of suitable guiding devices. The excess liquid may be removed from the thread by passing it over scraping-off devices, sponges and the like, and may then be led to the winding device by way of a common drying cylinder in the manner described above.
- 10 In some instances, it may be advisable to insert between the impregnating device and the actual heating and hardening device a step or means effecting a dehydration of the thread at increased temperature. By so doing agglutination and crystallization on the heating roller may be prevented.
- In the drawing:
- Fig. 1 is a diagrammatic cross-section of a machine for carrying out the novel process;
- 20 Fig. 2 is a partial diagrammatic section of a modified form of the invention.
- In Fig. 1 of the drawing in which like numerals of reference indicate like parts, 1 indicates the thread which is drawn from a cross-wound bobbin, 2, and passes over a thread break 3, on to heating rollers 4 and 5, arranged at an angle with respect to the bobbin 2.
- The thread passes over the heating cylinders 4 and 5, a plurality of times and is subsequently wound with constant speed upon a bobbin 6. Hardening liquid is sprayed upon the lower treating cylinder by means of a calibrated nozzle 7. That portion of the liquid which is not carried away by the thread 1, flows off along the lower cylinder 5 into the trough 8 in order to be used again if desired. The lower side of the upper cylinder 4 is heated by means of a gas burner 9.
- The thread 1, after having passed over the lower end of the cylinders is well saturated with 40 treating liquid and passes gradually into the heating zone of the drying roller where it is dried and gradually heated to a high temperature.
- With a uniform take-up speed the length of time of the heat treatment may be readily controlled, depending upon the number of windings of the thread around the cylinders and the degree of heating of the latter.
- During the passage of the thread through the air to the bobbin winding device 6, the thread 50 undergoes a cooling step and is thus preserved from injuries due to temperature after-effects.
- If desired the thread may be passed over an easily movable no-load roller 10, in order to be quickly and thoroughly cooled. The roller 10 provides a heat-absorbing surface over which the yarn is caused to pass continuously without substantial relative movement. A wetting-device 11 may be placed before the winding device, which effects a moistening of the thread with a small quantity of water or an oil emulsion or the like, prior to its winding.
- A suction hood 12 may be positioned adjacent to the drying device whereby suction slots extract the hot air above the gas burners.
- 65 As shown in Fig. 2 of the drawing the thread may be drawn from large packages such as cross-wound bobbins or cones, and first impregnated by drawing it through a device containing a hardening liquid. For this purpose the thread is first immersed in a trough 14 by being carried around a guide rod 15. The thread then passes from the trough to a guiding device having a sponge or felt body 16, whereby excessive liquid may be removed from the thread. As hereinbe-
- fore pointed out, other devices as are used for the continuous oiling and sizing of threads may be employed.
- If the device is intended for use on a big scale production, it is advisable to arrange a large number of operating places side by side and at a certain distance from each other. Both sides of the machine may also be utilized for operation and the numerous heating rollers on the two sides of the machine may be driven from a common gearing within a gear case 13 positioned in the lower part of the machine.
- The treating rollers 5 should of course consist of a material which is resistant to chemicals used.
- From the foregoing description, it is thought the complete operation, arrangement and process disclosed will be clear to those skilled in the art to which it relates.
- What I claim is:
1. In a machine for finishing yarn comprising a frame, roller means extending from the frame in an upwardly inclined direction, driving means for said rollers, means for moistening the roller means at the bottom and heating said roller means at the top thereof, and means for feeding yarn so as to cause it to progress in a helical path along said roller means from the bottom to the top thereof; a suction device extending above the roller means in spaced relation thereto, a freely movable cooling roller between the top of the roller means and the suction device and in contact with which the heated yarn is adapted to pass as it leaves the roller means, a re-moistening device, and a yarn collecting device, both the re-moistening device and the yarn collecting device being arranged to contact the yarn after it has been cooled and has moved beyond the suction device.
2. In a machine for finishing yarn comprising a frame, roller means extending from opposite sides of the frame in an upwardly inclined direction, driving means for said roller means, means for moistening the roller means at the bottom and heating said roller means at the top thereof, and means for feeding yarn so as to cause it to progress in a helical path along each of said roller means from the bottom to the top thereof; a suction device common to both sides of the frame and extending above each roller means in spaced relation thereto, a freely movable cooling roller between the top of each roller means and the suction device and in contact with which the heated yarn is adapted to pass as it leaves the roller means, a re-moistening device for each roller means, and a yarn collecting device for each roller means, both the re-moistening devices and the yarn collecting devices being arranged to contact the yarn after it has been cooled and has moved beyond the suction device.
3. In a process for the continuous sizing of artificial cellulosic yarn, the steps comprising saturating the yarn with sizing solution and drying it by applying heat thereto while it is passing in a helical path over rotating, impervious guiding surfaces to form a dried yarn; immediately thereafter cooling said dried yarn by causing it to pass continuously without substantial relative movement over a heat-absorbing surface; re-moistening the dried and cooled yarn; and finally collecting said yarn.
